CLAIM

The ornamental design for a robotic dog, as shown and described.

DESCRIPTION

FIG. 1 is a front view showing a first embodiment of our new design;

FIG. 2 is a rear view thereof;

FIG. 3 is a top plan view thereof;

FIG. 4 is a bottom plan view thereof;

FIG. 5 is a side view thereof, the opposite side being a mirror image thereof;

FIG. 6 is a perspective view of a second embodiment of our new design;

FIG. 7 is a side view thereof, the opposite side being a mirror image thereof;

FIG. 8 is a front view thereof;

FIG. 9 is a rear view thereof;

FIG. 10 is a top plan view thereof;

FIG. 11 is a bottom plan view thereof; and,

FIG. 12 is a side view thereof, the broken lines depicting the robotic dog in a sitting position, the solid lines depicting the robotic dog in a standing position, the opposite side being a mirror image thereof.
